UNITED STATES PATENT OFFICE.

WILLIAM S. MACLEWEE, OF YARDLEY, PENNSYLVANIA, ASSIGNOR TO CARRIE HOWELL
MACLEWEE, OF YARDLEY, PENNSYLVANIA.

FUSE-PLUG.

1,243,849.

Specification of Letters Patent. Patented Oct. 23, 1917.

Application filed November 23, 1915. Serial No. 63,041.

To all whom it may concern:

Be it known that I, WILLIAM S. MACLEWEE, a citizen of the United States, residing at Yardley, in the county of Bucks and State of Pennsylvania, have invented certain new and useful Improvements in Fuse-Plugs, of which the following is a specification.

My invention relates to improvements in fuse plugs and the object of my invention is to make a fuse plug which is simple in construction; which is non-breakable; and which can be manufactured at a very low cost, and a further object of my invention is to so construct the fuse plug that the fuse wire may be secured into place before the fuse plug is assembled. These together with various other novel features of construction and arrangements of the parts 20 which will be more fully hereinafter described and claimed constitute my invention.

Referring to the drawing; Figure 1, is a perspective view of my improved fuse plug; Fig. 2 is a central vertical section of the fuse plug; Fig. 3, is a perspective view of the base part detached and Fig. 4, is a vertical section of the several parts of the fuse plug detached.

In the drawings in which like references refer to like parts, 1 represents the cylindrical body portion which is made of insulating material and preferably of fiber.

Indentations 2, are formed in the upper 35 end of the body portion 1 for the purpose of forming ventilating spaces. Upon the upper end of the body portion is placed a transparent disk 3, which is held in place by the apertured metal cap 4, having a corrugated cylindrical flange 5. The corrugations formed in the cylindrical flange 5 of the cap 4, form ventilating spaces between the body portion 1 and the flange 5 of the cap. The cap 4 is secured upon the body 45 portion 1, by the indentations 6, which force the metal of the cap into the fiber body portion and securely hold the parts together.

The threaded shell 7, which is made of metal has an inwardly turned annular flange 8 upon the bottom thereof and upon which rests a fiber disk 9, which carries the contact button 10, to which the fuse wire 12 is soldered. A contact plate 13, which is formed integrally with the shell 7 is bent

inwardly and upon its inner end is soldered 55 the other end of the fuse wire 12.

The cylindrical body portion 1 is provided with a longitudinal cut or slot 14, (see Fig. 4), into which the contact plate 13, enters as shown in Figs. 1 and 2. The shell 7, can be forced upon the lower end of the body portion so tightly that the parts are securely held together, and it has been found in practice that it is unnecessary to provide any other fastening means. The contact arm 13, which projects through the slot 14 formed in the body portion would prevent the shell from turning upon the body portion.

The fiber disk 9, is larger in diameter 70 than the end of the body portion 1, so that the end of the latter presses against the edge of the disk 9 and securely holds the disk in place in the shell 7.

It will be seen that the fuse wire 12, can 75 be soldered at one end thereof to the contact button 10 before the parts are assembled, thus making sure that a good connection or contact is made. The disk 9 is then inserted into the shell 7 and the opposite 80 end of the fuse wire 12 is soldered to the contact arm 13, of the shell, which operation can readily be done as the parts are all accessible. The body portion is then inserted into the shell with the contact arm 13 85 entering the slot 14 formed in the body portion and the shell and the body portion are tightly forced together.

A fuse plug is thus formed of few parts which can be readily assembled; which is 90 strong and durable, properly ventilated and which can be manufactured at a low cost.

Having thus described my invention I claim and desire to secure by Letters Patent:

1. A fuse plug comprising a metal shell, a disk of insulating material inserted in the shell, a contact button in said disk, a contact plate projecting inwardly from the shell, a fuse wire between the contact button 100 and the said contact plate, and a body portion having a slot formed therein to receive said contact plate. 95

2. A fuse plug comprising a metal shell, a contact plate formed integrally with the 105 main part of the shell and bent inwardly, a fuse wire attached to the inner end of the contact plate, a body portion having a slot

formed therein to embrace the said contact plate, and a contact button located in the metal shell to which the opposite end of the fuse wire is attached.

- 5 3. A fuse plug comprising a cylindrical body portion having a longitudinal slot formed in one end thereof, a metal shell secured upon the end of the body portion having the said slot formed therein, a contact 10 plate formed upon the inner edge of the metal shell, said contact plate extending inwardly through the slot formed in the body

portion, a disk of insulating material in the metal shell, a contact button upon the disk, a fuse wire connected with the contact button and the contact plate on the metal shell, and a closure for the opposite end of the body portion.

In testimony whereof I have affixed my signature in presence of two witnesses.

WILLIAM S. MACLEWEE.
